UNITED STATES PATENT OFFICE.

HENRY P. SCHOFIELD, OF CHICAGO, ILLINOIS, ASSIGNOR TO COVEL MANUFACTURING COMPANY, OF CHICAGO, ILLINOIS, A CORPORATION OF ILLINOIS.

SAW-GUIDE.

SPECIFICATION forming part of Letters Patent No. 755,318, dated March 22, 1904.

Application filed May 27, 1903. Serial No. 158,946. (No model.)

To all whom it may concern:

Be it known that I, HENRY P. SCHOFIELD, a citizen of the United States, residing at Chicago, in the county of Cook and State of Illinois, have invented a new and useful Improvement in Saw-Guides, of which the following is a specification.

My invention relates particularly to saw-guides adapted to be arranged about a saw-sharpening machine for the purpose of supporting a band-saw while the sharpening operation is being carried on.

My primary object is to provide a device of this character which will permit ready insertion and removal of the saw, and yet will permit the saw to move freely in the guide.

The invention is illustrated in the accompanying drawings, in which—

Figure 1 represents an elevational view of my improved saw-guide supporting a fragment of a saw; Fig. 2, a broken view of the standard, taken, as indicated, at line 2 of Fig. 1; Fig. 3, a similar view of the opposite side of the standard, taken, as indicated, at line 3 of Fig. 1; Fig. 4, a broken vertical section taken, as indicated, at line 4 of Fig. 2; and Fig. 5 a broken section taken, as indicated, at line 5 of Fig. 1.

A description of the preferred construction is as follows: A represents a suitable base provided with a tubular standard A', having a vertical opening A²; A³, a member having a telescoping connection with the tubular portion A' and equipped with a rack a, exposed at the opening A²; A⁴, a shaft journaled in suitable bosses on the tubular portion A' and equipped with a pinion A⁵, meshing with the rack a and equipped also with a handle A⁶; A⁷, a set-screw for fixing the member A³ at any desired height; B, a guide-head provided with a depending stem B', journaled in a socket with which the upper end of the member A³ is provided; B², a grooved roller having a shaft b supported in the fixed portion of the head B; B³, fixed vertical guide members with which the head B is provided and which serve as guide-walls or bearings for one side of the saw, and B⁴ a pair of pivoted members coact-

ing with the members B³ and forming the guide walls or bearings for the opposite side 50 of the saw.

The head B is fixed in any desired position with relation to its standard or support by means of a set-screw c. The member A³ is provided with a suitable scale d, reading to 55 inches. The members B⁴ form, with the members B³, a guide-channel C for receiving the saw C'. Each of the members B⁴ is supported on a pivot f, extending parallel with the saw, and is provided at its base, adjacent to the pivot, 60 with a cam or extension f', which extends through a slot f² at the base of the corresponding member B³. The head B is equipped adjacent to the base portions of the members B³ and between the slots f² with levers f³, 65 supported on pivots f⁴ and having short cam-arms f⁵, which serve to engage the short arms or cams f' of the members B⁴ in the vertical position. This is clearly illustrated in Fig. 5. The channel C has at its bottom shoulders g, 70 which are formed at the inner sides of the stationary members B³. The grooved roller B² projects above these shoulders and supports the saw.

From the foregoing description it will be 75 understood that the saw may be entered in the channel and supported on the roller B², while the members B⁴ are in the dropped position, after which the members may be raised to the vertical standing position and 80 locked by the levers f³. The importance of this construction will be understood when it is explained that saws of this character are usually very heavy, making it a difficult operation to enter them into narrow guides. 85

It will be understood that changes in details of construction within the spirit of my invention may be made. Hence no undue limitation is to be understood by the foregoing detailed description. 90

What I regard as new, and desire to secure by Letters Patent, is—

1. A saw-guide, comprising a standard provided with a stationary guide member having perforations, pivoted guide members having 95 short arms at their lower ends entering said

perforations and capable of being dropped from their vertical position, and locking devices for engaging said arms supported on pivots adjacent to said perforations, for the purpose set forth.

2. A saw-guide, comprising a standard equipped with a guide-head having two vertical stationary guide members, a roller journaled in said head between said guide members, pivoted guide members opposed to said first-named guide members and having short cam-arms at their lower ends, and a pair of cam-levers supported on pivots perpendicular to said guide members, for the purpose set forth.

3. A saw-guide, comprising a base portion 15 having a tubular standard provided at one side of its upper portion with a slot and flanking lugs, a shaft journaled in said lugs, and equipped with a handle and pinion, a guide-head for a saw having a vertical guide-channel, and a stem swivelly supporting said guide-head and telescoping with said tubular standard and provided with a rack engaged by said pinion, for the purpose set forth.

HENRY P. SCHOFIELD.

In presence of—

W. B. DAVIES,

WALTER N. WINBERG.
